RECORD CONTROLLED ASSEMBLY JIG

Hans P. Luhn, Armonk, N. Y., assignor to International Business Machines Corporation, New York, N. Y., a corporation of New York

Application September 21, 1948, Serial No. 50,416

2 Claims. (Cl. 29—33)

1

This invention relates to assembly devices and more particularly to jigs for facilitating the wiring of a series of terminals in accordance with the indicia of a record card.

It is conventional and frequently desirable to store information in the form of selected connections to the terminals of selector switch levels and later scan these levels with the aid of suitable computing apparatus to read out and utilize the information stored.

Accordingly, it is a principal object of this invention to provide an assembly jig responsive to record card indicia for indicating terminals representative thereof and preparing the terminals to receive a soldered connection.

It is another object to provide an assembly jig for retaining selector switch levels having terminals thereon to be connected to other previously designated terminals representing like values wherein the jig automatically designates the position of the wires to be soldered to the selector switch level, so that they can be placed in proper position for connection to the previously designated terminals.

It is another object to provide an assembly jig of simple construction for effecting the transfer of a variety of information from a record card to a series of terminals, the jig including wire holding cutting and stripping means and terminal heating means for facilitating the connection of wires thereto.

Other objects of the invention will be pointed out in the following description and claims and illustrated in the accompanying drawings, which disclose, by way of example, the principle of the invention and the best mode which has been contemplated, of applying that principle.

Briefly, the invention includes a selector switch level holder; a series of light bulbs each disposed underneath one terminal of the selector switch level; a series of brushes actuated by an arm to scan a record card; a wire holder; rotatable heating means for heating selectively the individual terminals of the switch to receive soldered connections and a wire cutter and stripper displaced by the rotation of the arm to designate the position which the wires connected to the switch should occupy on the wire holder to facilitate connection of the switch level to preselected terminals.

In the drawings:

Fig. 1 is a top view showing one embodiment of the invention.

Fig. 2 is a cross-sectional view of the embodiment shown in Fig. 1 taken along the line 2—2

5 thereof, a portion of the wire cutter and stripper being cut away.

Fig. 3 is a cross-sectional view of the embodiment shown in Fig. 1 taken along the line 3—3 thereof.

Fig. 4 is an elevation view of the wire holding, cutting and stripping means shown in Fig. 1.

Fig. 5 is a top view of the selector switch level shown in Fig. 1 and a series of terminals to which the terminals of the switch level are to be connected.

Referring more particularly to the drawings, the structural arrangement of the entire jig and cooperating parts can be appreciated from Fig. 1.

15 The entire jig is supported by a base plate 10. Rectangular card retaining plate 11 of conductive material is fastened to the base plate 10 by screws 12. Insulating plate 13 (Fig. 3) is secured intermediate the plates 10 and 11 by the same screws 12. Leaf springs 14 are fastened to the card retaining plate 11 by screws 15 extending through each spring near one of its ends and through insulating washer plates 16. Record card 17 is held snugly against the retaining plate 11 by the leaf springs 14, the card fitting within the rim 18 of plate 11.

20 Supporting member 19 is fixedly mounted on the base plate 10 so that it extends parallel thereto over the card retaining plate 11 and record card 17 retained thereon. A plate 20 is slidably mounted on supporting member 19 by gibbs 21 secured to the plate 20 by screws 22.

25 Arm 23 is pivotally mounted on the base plate 10 at 29a and extends parallel and in spaced relation to the base plate. The other end of the arm 23 contains a slot 24 adapted to receive a shouldered stud 25 and be held in engagement therewith by washers 26 and 27 and a screw 28 (Fig. 3). Obviously, slot 24 permits the plate 20 to be slidably moved along the supporting member 19 upon the rotation of the arm 23. Arm 29 is pivotally mounted at 29a and affixed to and rotatable with the arm 23 to form a bell-crank lever. A knob 30 is affixed near the other end of the arm 29 to permit easy rotation of the bell crank. A slot 31 is provided in the arm 29 to permit the rotation of the arm to impart translatory motion to a member slidably engaged with the slot.

30 The lower left hand portion of Fig. 1 shows the supports 10a affixed in spaced relation on the base plate 10. Plate 32 is affixed by screws 33 to each support 10a to span the distance therebetween. A shaft 34 slidably mounted in the supports 10a is slidably engaged in the slot

31 of arm 29. Stops 35 and 36 affixed to the shaft 34 are provided to limit the travel of the shaft 34 to the left and right, respectively, the shaft being shown in its extreme right position. A wire stripper and cutter, generally designated by 37, is rotatably mounted on shaft 34 intermediate stops 38 and 39 and urged to a floating position therebetween by springs 40 and 41. A series of ten detent notches 42, corresponding to the index positions of the card 17, are arranged to engage the detent member 43 and are provided to permit selective positioning of the shaft.

The dotted position of the arm 29 and the stop 35 represent their extreme left positions and are shown to facilitate the description of the operation of the invention hereinafter.

Referring to Figs. 1 and 2 a disk plate 44 is fixedly mounted on a post 45 secured to the base plate 10. The top half of the peripheries of the disk plate 44 (Fig. 1) is divided into twenty equally spaced parts designated 1-20, respectively, to denote the columnar positions of the record card 17. A series of twenty electric light bulbs 46-65 are secured near the bottom half of the periphery of the disk plate 44 (Fig. 1). An arm 66 is rotatably mounted adjacent to the plate 10 on the post 45. A member 67 is attached to one end of arm 66 and carries a detent 68 engaged with an associated notch in the periphery of the disk plate 44. A notch is provided opposite each designation 1-20 on the disk plate 44. A pointer 69 is attached to the other end of arm 66 and a handle 70 is attached to the member 67 to permit rotation of the pointer to designate any bulb 46-65. A slot 71 in the disk plate 44 permits the rotation of the pointer 69.

An annular ring 72 is fixedly mounted on the plate 44 concentric with the post 45. A selector switch level 73 (Fig. 5) is positioned on ring 72 with its terminals 76-96 opposite the corresponding light bulbs 46-65 except that there is no bulb opposite the common or ground terminal 96. The switch 73 is held in position by any suitable means such as posts (not shown) extending from the plate 44 through hole 97 (Fig. 5) in the switch 73. A cap 99 having a knurled knob 100 fits over the ring 72 and holds the switch 73 against vertical movement. A groove 101 is provided in the cap 99 to receive the posts extending through the switch plates 98. Posts 102 and 103 are affixed to the cap 99 and engage the post 45 and plate 44, respectively, to provide for quick and accurate assembly of the cap with the ring 72 and switch level 73.

Pipes 104, 105 and 106 are mounted on the arm 66 and rotatable therewith, upon the rotation of the handle 70, to be immediately underneath any one of the terminals 76-96. The pipes 104 and 105 contain gas and air, respectively, which are combined to maintain a flame used to condition the selected terminals 76-96 for soldering. The pipe 106 contains cool air which is utilized to cool quickly the soldered terminals. An opening 107 is provided to permit the rotation of pipes 104-106 with the arm 66, while still maintaining their connections to their respective sources of supply.

Wire guides 108 are affixed to the plate 44 and extend upwards therefrom to provide a convenient means for separating and bending the wires soldered to the terminals 76-96.

The wire holding means generally designated

as 109 is attached to the plate 32 and comprises the stationary plate 110 (Fig. 4) having a series of slots 111-120, plate 121 slidably mounted thereon, and a manually operable cam assembly 122. The plate 121 has a series of teeth 123 each having a protruding portion 123a formed to mate with the portion 110a of the plate 110. To effect a holding of a wire conductor, it is inserted in the desired one of the slots 111-120 which correspond to the index positions of the record card 17. Prior to such insertion, the cam assembly is positioned with the roller 121a of plate 121 on the intermediate land of the cam 122 and the protruding portions 123a prevent the conductors from falling into the bottom portion of the slots 111-120.

The cam assembly is then rotated to the position shown to force the plate 121 to the right thereby compressing the conductor between a tooth 123 and the side of a corresponding slot to hold it firmly. A spring 124 is attached at one end to the stationary plate 110 and at its other end to the slideable plate 121 and urges the plate 121 against the periphery of the cam. Hence, when the peripheral portion of the cam nearest its center is placed against the plate 121 by rotating the handle of the cam assembly clockwise, the plate 121 is in its extreme left hand position and the conductors are readily placed in the slots 113-120.

The novel wire cutter and stripper is rotatably secured on the shaft 34 by casing 125. A slot 126 having a sharpened edge is provided to receive a wire conductor. Cutter blade 127 is actuated by button 128 to effect a cutting of the conductor. Spring 129 (Fig. 2) urges the blade 127 into contiguity with the sharpened edge of the slot 126 to ensure easy and uniform cutting of the conductor. The button 130 is stationary and is provided to serve as a hand grip to facilitate the moving of the button 128.

A plate 131 (Fig. 2) is attached to the casing 125 and defines a slot 132 having two sharp edges of the type ordinarily used to strip insulation from wire conductors. A button 133 is attached to the member 134 which is rotatably mounted on a pin 135. A portion 134a of member 134 contains a slot which is arranged to mate with slot 132 of member 131 when the button 133 is rotated about the pin 135.

When a wire is to be stripped it is placed in the slot 132 and the slot 134a mated therewith and so held to engage the wire with the sharp edges of the slot 132. The entire cutter and stripper is then rotated about the shaft 34 to strip the insulation from the wire conductor. The portion 125a of the casing 125 is provided to effect easy rotation of the cutter and stripper about the shaft 34.

Referring to Fig. 3, an insulating member 136 is attached to the plate 20 and adapted to carry a series of twenty wire brushes 137 corresponding to the columnar positions of the record card 17. Plates 138 and 139 are mounted in the member 136 and are slotted to receive the vertically extending portion of the brush 137 corresponding thereto, there being a slot in each member 138 and 139 corresponding to each brush 137. These slots permit the brushes 137 to be supported by the plates 138 and 139 and prevents any substantial movement of them except in a vertical direction, thereby ensuring that each brush will scan only one columnar position on the card.

When the arm 23 is rotated, the plate 20 is

moved relative to the supporting member 19 and the brushes 137 scan or sweep over the surface of the record card 17. An electrical circuit is completed through the retaining plate 11 and each brush 137 to a corresponding one of the bulbs 46-65. This circuit is not shown in the drawings, since any conventional arrangement including simple conductive connections between the brushes and bulbs and a source of voltage supply is sufficient.

The switch level 73 comprises one of several selector switch levels. This invention facilitates and insures the proper connection of all these levels for use in a computing machine or other preselected apparatus.

Referring to Fig. 5, the terminals 76-95 of the switch level 73 are wired with conductors in accordance with the indicia of a record card in the manner set forth hereinafter. After the conductors are soldered to the terminals of the selector switch level, they are connected at their other end to terminals or bus bars corresponding, respectively, to the indicia of the record card. In other words, if indicia representing the numeral 8 causes the bulb 61 (Fig. 1) to be lighted, a wire is soldered to the terminal 91 of the switch level and, after the wiring of the switch level is completed, the other end of this wire is connected to the terminal 8 of the terminal strip shown at the right of Fig. 5.

To insure clarity, the operation of the invention will be set forth by way of example. Suppose it is desired to store, on a selector switch, the values contained in the following table:

Values To Be Stored					Corresponding Card Column
4	6	2	7	2	1
3	5	1	0	2	2
6	5	3	8	9	3
8	9	4	5	7	4
7	0	5	4	8	5
7	1	6	8	0	6
2	6	3	9	1	7

A record card is prepared to indicate the values contained in each of the five columns of the table. For purposes of illustration, the novel method followed relative to the last column will be described in detail, the methods followed relative to the remaining columns being similar to that followed for the last column.

It is seen from Fig. 1 that values representing 0-9 may be punched in those respective index positions of the record card 17 in any one of several ways of which the following is one of the most common. The "2" value is represented by a punched hole in the card at the "2" index position in the first column of a field of the card, that column being scanned by the left hand brush 137 (Fig. 1). The other "2" value is represented by a punched hole in the card at the "2" index position in the second column which is scanned by the second brush 137 (Fig. 1) from the left, the "9" value is represented by a punched hole at the "9" index position and the third column the "7" value is represented by a punched hole at the "7" index position and the fourth column. This procedure is repeated until all the desired values are punched in the card and, when the card is punched to correspond to the last column (i. e., the values 2, 2, 9, 7, 8, 0, and 1), the arm 29 is rotated clockwise until it is in its extreme left po-

sition (shown by dotted lines in Fig. 1) and the punched record card inserted underneath the leaf springs 14 and within the rim 18 of the retaining plate 11. The arm 29 is then rotated counterclockwise until the first notch 42 engages the detent member 43 to place the brushes on the card in the 9 index position. The third brush 137 from the left makes contact with the retaining plate 11 and completes a circuit to the bulb 63 causing it to light. The lighting of the bulb 63 indicates that a wire conductor should be soldered to the corresponding terminal 93 of the selector switch level 73. The handle 70 is rotated to the "3" position with the pointer 69 intermediate the bulb 63 and the terminal 93. By any suitable means, for example a pedal, a gas flame supplied from the pipes 104 and 105 is directed onto the terminal 93.

When the terminal 93 is sufficiently heated, the flame is removed and a wire conductor, properly stripped by the use of wire stripper 140, is soldered to the terminal 93. Cool air is then blown through the pipe 106 upon the terminal 93 to facilitate its cooling. The wire conductor is then pulled around a pin 108 nearest the terminal 93 and placed in the slot of the wire holder 109 opposite the slot 126 of the wire cutter and stripper 37. When the shaft 34 is in this position with the extreme right hand notch 42 corresponding to the first index position engaging the latch member 43, the slot 126 is opposite the slot 111 of the wire holder. After the conductor is placed in the slot 111, the cam assembly 122 is rotated to the position shown in Fig. 4 to clamp the conductor firmly in position. The conductor is then placed into the slot 126 and cut by actuating the cutter blade 127 as previously described. The button 133 is then rotated until the slot of the portion 134a presses the conductor against the slot 126. While urging the button 133 to this position, the entire assembly 37 is rotated from the wire holder 109 to strip the insulation from the wire so that it may be connected to another terminal, such connection is described hereinafter.

The knob 30 is then rotated counterclockwise until the second notch 42 from the right engages the latch member 43. The brushes 137 are now on the "8" index position of the card 17 and the fifth brush from the left contacts the retaining plate 11 to light the bulb 61. The handle 70 is rotated to the "5" position and a wire conductor soldered to the terminal 91 as previously described. The conductor is threaded around the nearest pin 108 and clamped in the slot 112 and cut and stripped in the same manner as the conductor soldered to the terminal 94.

The knob 30 is then rotated counterclockwise until the next notch 42 engages the latch member 43. The brushes 137 are now on the "7" index position and the fourth brush from the left contacts plate 11 to light the bulb 62. The handle 70 is rotated to the "4" position and a conductor soldered to the terminal 92 as previously described. The conductor is then placed in the slot 113 opposite the slot 126 and cut and stripped.

The knob 30 is then rotated step by step until the brushes 137 scan the "6," "5," "4," and "3" index positions. When this is done, none of the bulbs light thereby indicating that no connections corresponding to these numerals are to be made to the switch level 73.

The knob 30 is then rotated to place the brushes on the "2" index position. The first and second brushes from the left contact the plate 11 and cause the bulbs 64 and 65 to light and the designated terminals 94 and 95 are connected together and a single conductor soldered thereto, placed in the slot 118 now opposite the slot 126, cut and stripped.

The knob 30 is then rotated until the brushes are on the "1" index position and the seventh brush from the left contacts the plate 11 and causes the bulb 59 to light. A conductor is then soldered to the terminal 89, placed in the slot 119 opposite the slot 126, cut and stripped.

The knob 30 is then rotated to place the brushes on the "0" index position and the sixth brush from the left contacts the plate 11 and causes the bulb 60 to light. A conductor is then soldered to the terminal 90, placed in the slot 120 opposite the slot 126, cut and stripped.

The conductors connected to the switch level 73 each now have their loose end extending from the wire holder 109. The relative positions of the conductors are shown diagrammatically in Fig. 5. These loose ends are to be connected to terminals or bus bars to which they correspond; that is to say, the conductors corresponding to the values 0-9 connected to the terminals of the selector switch level 73 are connected at their other end to the terminals or bus bars corresponding, respectively, to the values 0-9. These terminals mounted on terminal board 141 (Fig. 5) are designated 0-9, respectively, which are the values to which they correspond. When the terminal board with the terminal 9 on the left is placed in contiguity with the wire holder 109, each conductor is opposite the terminals to which it corresponds as shown in Fig. 5. The conductors may be soldered to the corresponding terminals of the terminal board while it is held against the holder 109 or the cap 99 may be removed and the switch level disengaged for soldering the conductors to the terminals in any convenient manner.

The above procedure is repeated for the remaining four columns, there being produced a selectively wired switch level corresponding to each column of the table. All of the switch levels can then be assembled to form a selector switch from which the various values set forth in each row of the table may be readily obtained. The apparatus and procedure required to read out these values from the selector switch do not constitute part of this invention.

It is now apparent that the invention is extremely useful in facilitating the storing of information in that the record cards may be punched in advance and the proper connections made by an inexperienced person without requiring a checking thereof or supervision of any kind.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. An assembly jig for wiring selector switch levels to correspond to the indicia of a record

card including a support formed to receive a selector switch level having a plurality of terminals extending from its periphery; a cap engageable with and disengageable from said support for fixedly positioning said level; a wire holder comprising a plurality of wire holding members mounted in spaced relation to said support, each of said wire holding members corresponding to an index position on said card; a unitary control operable to cause said members to clamp and release wire conductors; an electric glow device mounted adjacent to each terminal of the selector switch level, each said device comprising a bulb connected to be responsive to indicia in one column of said card; a shaft slidably mounted in juxtaposition with said wire holder; detent means for retaining said shaft in any of a plurality of positions corresponding to the columnar positions on the card; a conductive plate for receiving the record card; resilient means for retaining the card in a stationary position on said plate; a plurality of brushes corresponding, respectively, to the columnar positions on said record card and slidably mounted to scan the card; a circuit connection from each brush to the corresponding glow device to energize said device when that brush contacts the conductive plate thereby completing an electrical circuit including said glow device; and a bell crank for imparting translatory motion to said brushes and said shaft.

2. An assembly jig for wiring selector switch levels to correspond to the indicia of a record card including a support formed to receive a selector switch level having a plurality of terminals extending from its periphery; a cap engageable with and disengageable from said support for fixedly positioning said level; a wire holder comprising a plurality of wire holding members mounted in spaced relation to said support, each of said wire holding members corresponding to an index position on said card; an electric glow device mounted adjacent to each terminal of the selector switch level, each said device comprising a bulb connected to be responsive to the sensing of indicia in a different column of said card; a shaft slidably mounted in juxtaposition with said wire holder; a wire cutter and stripper rotatably mounted on said shaft and slidably therewith, said cutter including a slotted member for receiving a conductor, a cutter blade, means for moving the cutter blade along one face of the slotted member and resilient means for holding the blade contiguous with the slotted member, said stripper including a second slotted member having a slot aligned with the slot in said first-mentioned slotted member and a member of the wire holder, a third slotted member rotatably mounted in substantially perpendicular spaced relation to said second member, means for rotating said third slotted member to mate the slot thereof with the slot of said second slotted member to clamp a conductor therebetween and means for rotating said cutter and stripper to strip the insulation from a length of the conductor; detent means for retaining said shaft in any of a plurality of positions corresponding to the columnar positions on the card thereby providing for the definite step-by-step translatory movement of said shaft, record card receiving means for fixedly positioning said card; a plurality of indicia sensing means corresponding respectively to the columnar positions on said card and slidably mounted to scan the card; an electrical cir-

cuit connecting each indicia sensing means to the corresponding glow device, said circuit being closed when that sensing means contacts the indicia of said card; and a bell crank for imparting translatory motion to said indicia sensing means and said shaft so that the step-by-step rotation of said bell crank causes the index positions of said card to be scanned thereby closing said electrical circuit to energize said glow devices to indicate the terminal of said switch level adjacent thereto and indicating the wire holding member corresponding to said indicia, each said wire holding members being indicated by its proximity to said stripper and cutter movable with said shaft.
